WITNESS:

ATTORNEY

UNITED STATES PATENT OFFICE.

FREDERICK A. CALKINS, OF MCKENZIE, NORTH DAKOTA.

RHEOSTAT.

Application filed January 28, 1924. Serial No. 689,167.

To all whom it may concern:

Be it known that I, FREDERICK A. CALKINS, a citizen of the United States, residing at McKenzie, in the county of Burleigh and 5 State of North Dakota, have invented new and useful Improvements in Rheostats, of which the following is a specification.

This invention relates to electrical control devices, particularly to rheostats, and has 10 for its object the provision of a novel device of this character designed particularly for use in controlling current to the filament of a vacuum tube used in radio reception, the construction being such that a very accurate 15 and delicate adjustment may be had so that the best results may be obtained from even the most critical tubes.

An important object is the provision of a device of this character which is so constructed 20 that the current may be split so that the device will act the same as two rheostats.

Another object is the provision of a device 25 of this character which will be simple and inexpensive in manufacture, easy to adjust, positive in action, efficient and durable in service and a general improvement in the art.

With the above and other objects and advantages in view the invention consists in 30 the details of construction to be hereinafter more fully described and claimed and illustrated in the accompanying drawings, in which:

35 Figure 1 is a front elevation,
Figure 2 is a top plan view,
Figure 3 is a rear elevation,

Figure 4 is a longitudinal section on the line 4—4 of Figure 2,

40 Figure 5 is a cross section on the line 5—5 of Figure 2,

Figure 6 is a cross section on the line 6—6 of Figure 2,

45 Figure 7 is a detail perspective view of one of the conductor arms,

Figure 8 is a detail perspective view of the slider,

Figure 9 is a detail section showing the device mounted upon a panel,

50 Figure 10 is a diagram of a circuit arrangement,

Figure 11 is a diagram of a modified circuit.

55 Referring more particularly to the drawings I have shown the device as comprising front and back plates or panels 10 and 11

which may be constructed of bakelite or any other suitable insulating material and of any proper size and shape. These members are connected by spaced parallel rods 39 12 secured in any desired manner as for instance by means of nuts 13 threaded thereon. Journaled centrally through both panel members 10 and 11 is a screw 14 having one end carrying a pinion 15 and its other end 65 equipped with a control knob 16. It is really intended that this entire device be mounted at the rear of the supporting panel of a radio set and for this reason the front member 10 is preferably provided with holes 17 70 for the passage of suitable securing bolts or the like for effecting mounting. For the same reason, the forward end of the shaft or screw 14 projects considerably beyond the front member 10 so that the control knob 75 16 will be located in advance of the supporting panel of the set. Figure 9 shows a detail section through such a panel A having my device applied thereto and held by the bolts B. It should be understood however 80 that the device might be provided with a base or casing so as to be an enclosed instrument not requiring panel mounting, such a change being well within the spirit of the invention.

85 Journaled through the front and back members 10 and 11 at opposite sides of the central screw 14 are supporting rods 18 of insulating material equipped at their rear ends with gears 19 meshing with the pinion 90 15 so as to be turned when the screw 14 is turned. Secured to and wrapped about these rods or cores 18 are high resistance wires 20 which have their ends suitably fastened so as to prevent unwinding. In actual 95 practice one end of each wire 20 may be passed through a hole 21 in the rod 18 and bent over to effect holding, while the other end is secured to a metallic collar 22 fastened onto the rod near the associated gear 19. 100

At the rear side of the rear member 13 I provide three terminal clips 23, 24 and 25, the first one of which is connected with the screw 14, while the latter two are connected with the rods 12. Secured to each rod 12 is an arm 26 terminating in a fork 27 engaged upon the adjacent or associated collar 22 for electrically connecting the high resistance wires 20 with the connectors or clips 24 and 25. 105

110 Mounted on the screw 14 is a slider formed as a metal block 28 having a thread-

ed hole into which the screw 14 is threaded. Carried by this block are laterally extending spring arms 29 which have their outer end portions curved to define contacts bearing upon the wires or coils 20. These contacts are preferably ribbed as shown at 30 for insuring proper contact.

In the use of the device, it is interposed in a circuit as indicated in Figure 10 which shows one terminal of a battery C connected by a wire D with the clip 24, with the clip 25 connected by a wire E with one filament terminal of a vacuum tube or the like to be energized, the other terminal of which is connected by a wire F with the remaining terminal of the battery. In the operation it will be seen that the current will flow from the battery, through the wire D, clip 24, associated rod 12, arm 26, collar 22, associated wire 20, through the slider to the other wire 20 and other forked arm to the rod 12 associated therewith and from the clip 25 through the wire E to the vacuum tube. The circuit to the filament of the latter being completed by the wire F. It should be mentioned that the clips 23, 24 and 25 might be replaced by binding posts or their equivalent or may be replaced by simple terminal lugs to which connections may be made by soldering, all of these details being immaterial. By making a connection with the central clip 23, it is apparent that the device can be used as two rheostats though the resistance in this instance will naturally be only one-half in each circuit. In making use of this manner of connection, the connection from the battery is made to the intermediate clip 23 and the connections to the two tubes or other device to be operated should be made by wires leading from the clips 24 and 25 respectively. This modified circuit arrangement and use of the device is illustrated in Figure 11.

In the operation it is apparent that by turning the knob 16, the rotation of the screw 14 will move the slider along the re-

sistance coils, thus increasing or decreasing the length of wire in the circuit. Furthermore the rotation of the screw turns the gears 19 and consequently the rods 18 carrying the resistance wire so that the contact of the wires with the contacts of the slider will be continuous and the points constantly changing as the screw is turned. In actual practice I have discovered that the most minute adjustments may thus be accomplished and the current varied with such accuracy and delicacy as to insure maximum efficiency of the tubes even though they may be of a highly critical type. While tubes are referred to, it is obvious that the device may be used for controlling electric current to any devices wherein fine adjustment is essential.

While I have shown and described the preferred embodiment of my invention it is of course to be understood that I reserve the right to make such changes in the form, construction and arrangement of parts as will not depart from the spirit of the invention or the scope of the subjoined claim.

Having thus described my invention I claim:

A device of the character described comprising front and rear members arranged in space relation, spaced parallel resistance coils journally mounted between said front and rear members, a screw journaled centrally through said front and rear members and located between said resistance coils, intermeshing gears on said coils and screw for effecting simultaneous rotation of all, a slider threaded onto the screw and having its end portions bearing against said coils, rods secured to said front and rear members and located in spaced relation to and outwardly of said coils, and contacts carried by said rods and bearing against the coils.

In testimony whereof I affix my signature.

FREDERICK A. CALKINS.
